UNITED STATES PATENT OFFICE.

JOSEPH L. KLEIN, OF ST. LOUIS, MISSOURI.

DESIGN FOR A JUG.

61,415.

Specification for Design. Patented Aug. 29, 1922.

Application filed October 17, 1921. Serial No. 508,380. Term of patent 14 years.

To all whom it may concern:

Be it known that I, JOSEPH L. KLEIN, a citizen of the United States of America, residing at 118 Walnut St., in the city of St. Louis and State of Missouri, have invented a new, original, and ornamental Design for Jugs, of which the following is a specification, reference being had to the accompanying drawings, forming part thereof.

Fig. I is a plan view.

Fig. II is a side elevation.

Fig. III is an edge elevation.

I claim:

The ornamental design for a jug, as shown.

JOSEPH L. KLEIN,
